CLAIM

The ornamental design for a chlorine tab dispenser, as shown and described.

DESCRIPTION

FIG. 1 is a front perspective view of the chlorine tab dispenser in a closed orientation, showing the new design; FIG. 2 is a rear perspective view thereof; FIG. 3 is a left side view thereof; FIG. 4 is a front view thereof; FIG. 5 is a right side view thereof; FIG. 6 is a bottom view thereof; FIG. 7 is top view thereof; FIG. 8 is a top view of the chlorine tab dispenser in an open orientation with openings covered, showing the new design; FIG. 9 is a top perspective view of the chlorine tab dispenser in an open orientation with openings covered; FIG. 10 is a rear perspective view of the chlorine tab dispenser in an open orientation; FIG. 11 is a top perspective view of the chlorine tab dispenser in an open orientation with openings uncovered; and, FIG. 12 is a top view of the chlorine tab dispenser in an open orientation with openings uncovered. The broken line showing of a chlorine tab dispenser is included for the purpose of illustrating portions of the article and forms no part of the claimed design.

1 Claim, 4 Drawing Sheets
